UNITED STATES PATENT OFFICE.

OLUF BUHL, OF NEWELL, IOWA.

FIREARM.

1,395,903.

Specification of Letters Patent.

Patented Nov. 1, 1921.

Application filed December 31, 1920. Serial No. 434,330.

To all whom it may concern:

Be it known that I, OLUF BUHL, a subject of the King of Denmark, residing at Newell, in the county of Buena Vista and State of 5 Iowa, have invented new and useful Improvements in Firearms, of which the following is a specification.

My present invention has for its object the provision of a shotgun or other fire arm 10 embodying such a construction that it may be fired by slight pressure against a button or buttons at the upper side of the hand grip of the fire arm, this being materially advantageous inasmuch as it does away with 15 projections likely to catch against weeds, brush or wire and cause premature discharge, and also because it does not interfere in any measure with the aiming of the fire arm. The improvement is further advant- 20 ageous inasmuch as the fire arm is fired without affecting the grip of the user on the hand grip of the fire arm.

To the attainment of the foregoing, the invention consists in the improvement as 25 hereinafter described and definitely claimed.

In the accompanying drawing, forming part hereof:

The figure is a sectional perspective of so 30 much of a shotgun as is necessary to illustrate my invention; the shotgun being of double barrel type.

Referring by numerals to the said drawing:

1 indicates the stock of the fire arm, 35 equipped with a hand grip 2, and 3, 3 are the barrels of the fire arm; the said barrels being connected with the stock in the ordinary manner or in any other manner compatible with the purpose of my invention.

40 Appropriately mounted and movable in the upper portion of the hand grip 2 of the fire arm are pins 4, having heads 5 at their outer and rear ends. The said pins 4 are movable rectilinearly, and their inner ends 45 are opposed to the upstanding arms 6 of longitudinally arranged sears which are pivotally mounted at 7 and are provided with forwardly reaching arms 8. The said arms 8 are opposed at their forward ends to abut- 50 ments 9 on firing hammers 10 which are preferably of general hook-shape and are pointed at their ends as indicated by 11.

The firing hammers 10 are pivoted to and carried by a transverse shaft 12 which is mounted in the stock and is equipped with 55 a torsional spring or springs 13 constructed and arranged to be placed under tension by retraction of the firing hammers 10, and to forcibly swing the said hammers forwardly when the hammers are released from the 60 arms 8 of the sears. Any appropriate means such as protruding finger pieces 14 may be employed for retracting the hammers 10 and placing their springs under tension while 65 engaging the firing hammers with the forwardly reaching arms of the sears.

My novel fire arm is "cocked" in the manner indicated in the foregoing, and from this it follows that all that is necessary to fire the charge in either barrel of the fire 70 arm is to exert a slight inward pressure on the pin 4 complementary to the said barrel.

It will be manifest from the foregoing that only slight pressure on either of the pins 4 is necessary to disengage its sear from 75 the hammer 10, and that therefore the firing of the fire arm will not be attended by any alteration of aim, nor will it diminish in any degree the grip that the user has upon the hand grip 2 of the fire arm.

Having described my invention, what I claim and desire to secure by Letters-Patent, is:

A fire arm comprising a stock, a swinging firing hammer having a rear abutment and 80 also having a transverse shaft and means on the shaft and at the side of the stock for the retraction of the hammer, a spring about the transverse shaft to impel the firing hammer forwardly; said spring being tensioned 85 by the retraction of the firing hammer and the attendant racking of the shaft, a longitudinally-arranged sear pivoted in the stock and having a forwardly-reaching hammer-engaging arm and also having a rear up- 90 standing arm, and a pin guided in the stock and opposed at its inner and forward end to the rear side of the upstanding arm of the sear; said pin being designed to be pressed inwardly and forwardly by the user of the 95 fire arm.

In testimony whereof, I affix my signature.

OLUF BUHL.
